UNITED STATES PATENT OFFICE.

MORRIS BERNHARD, OF BUFFALO, NEW YORK.

DESIGN FOR A PORTIÈRE.

SPECIFICATION forming part of Design No. 29,209, dated August 9, 1898.

Application filed July 5, 1898. Serial No. 685,208. Term of patent 7 years.

To all whom it may concern:

Be it known that I, MORRIS BERNHARD, a citizen of the United States, residing at Buffalo, in the county of Erie and State of New York, have invented and produced a new and original Design for Portières, of which the following is a specification, reference being had to the accompanying drawing, forming a part thereof.

This design relates to the ornamentation of portières which are constructed of cords or strands.

The accompanying drawing is a face view of a portière embodying my design.

The leading or characteristic feature of my design consists of a number of transverse rows of oblique or zigzag cords extending at intervals across each of the pendent portions of the portière, arranged on opposite sides of the opening thereof, which rows of oblique cords divide each of said pendent portions into a number of rectangular panels.

Referring to the drawing, A is the head or top portion of the portière, which forms no part of my design.

B are the two pendent portions or sections of the portière which extend downward from the top A, and C is the opening or passage between the pendent sections.

D represents the horizontal rows of oblique or zigzag cords extending across the pendent sections B of the portière and arranged at suitable intervals, giving each section the appearance of being divided into a number of rectangular panels. In the portière shown in the drawing two rows of such oblique cords extend across each section, dividing the section into three panels D' D² D³. The oblique cords of each row D extend across the space between adjacent strands of the depending portière-sections, and at the adjoining ends of the oblique cords are arranged frills or ornamental enlargements e.

f represents a row of tassels extending across the top of the passage C, and g rows of tassels depending from the lower ends of the cords which form the pendent sections of the portière.

What I claim is—

The design for a cord portière, substantially as herein shown and described.

Witness my hand this 10th day of June, 1898.

MORRIS BERNHARD.
